(57) **CLAIM**

The ornamental design for a head shape for squirting toy, as shown and described.

DESCRIPTION

FIG. 1 is a perspective view of a squirting toy having a head shaped handle showing my new design;

FIG. 2 is a front view thereof;

FIG. 3 is a left side view thereof; and,

FIG. 4 is a rear view thereof.

The broken lines in the head area of the FIGS. 1-3 represent portions of the design that form no part of the claim. All other broken lines illustrate the environment in which the design resides. None of the broken lines form a part of the claim.
